UNITED STATES PATENT OFFICE.

WILLIAM A. RIDDELL, OF FREDERICK, MARYLAND.

SEPARATING OR CLASSIFYING MACHINE.

Application filed December 19, 1925. Serial No. 74,501.

My invention relates broadly to the construction of classifying, separating and assorting machinery and more particularly to the construction of a machine for separating 5 solid material into selected sizes.

One of the objects of my invention is to provide a separator of granular material in which a plurality of driven rolls are arranged on an inclined plane and the material 10 passed over the rolls for separating the more finely divided particles from the larger lumps and granules.

Another object of my invention is to provide a construction of separating machine 15 for granular material, in which a plurality of driven rolls are arranged on an incline with means for passing the material to be separated over the rolls and preventing the material from being carried to one side of 20 the separator by reason of the continued rotation of the rolls.

Still another object of my invention is to provide a separating machine utilizing a plurality of driven rolls which may be adjusted in space relationship one with respect 25 to another with means directly over the several rolls for preventing material which is passed over the rolls from being carried to one side of the separator by movement of 30 the rolls.

A further object of my invention is to provide a separator construction which is adjustable to select various sizes of material which is to be classified with adjustable 35 means for controlling the passage of material to be classified in such manner that the selected size of material may be obtained separate and apart from other sizes of material.

40 Other and further objects of my invention will be understood from the specification hereinafter following by reference to the accompanying drawings, in which:

Figure 1 is a side elevation of the separating machine of my invention; Fig. 2 is a partial cross sectional view taken through the separating machine of my invention, showing the adjustable separating plates which I provide over each of the separating 45 rolls in the machine; Fig. 3 is a plan view illustrating the arrangement of parts in the separating machine; Fig. 4 is a cross-sectional view taken through the separator on line 4—4 of Figs. 2 and 3; Fig. 5 is a fragmentary perspective view partially in cross-section showing the hopper of the separating 50 55 60 65 70 75 80 85 90 95 100 105 110

machine in which the material to be separated is deposited; and Fig. 6 is a partial cross-sectional view showing the arrangement of the adjustably spaced rollers and the vertically adjustable separating plates which are positioned over the rollers.

Referring to the drawings in more detail, reference characters 1 and 2 represent the longitudinally extending side frames of the separator to which are secured the laterally extending frame members 3 and 4. The frame members 3 and 4 are slotted at 5 and 6 respectively and adjustable bearing members arranged therein for the journaling of the separator rolls. I have represented bearing members 7, 8, 9, 10, 11 and 12 adjustably positioned in slot 6 of the end frame member 4, in such manner that they may be set on selected centers by loosening bolt members 7^a, 8^a, 9^a, 10^a, 11^a and 12^a respectively and sliding the bearings along the frame end member 4. The bearings may also be longitudinally adjustable with respect to the separator frame by means of the inclined plate bearing surface 7^b, 8^b, 9^b, 10^b, 11^b and 12^b. At the opposite end of the separator frame and adjustably positioned in slot 5 of the end frame member 3, I provide bearings 14, 15, 16, 17, 18 and 19. These bearings may be similarly adjusted by means of bolt members, as described in connection with bearings 7 to 12 and as represented by the adjustable bolt member 19^b in Figs. 1 and 2. The bearings form journals for the separator rolls 20, 21, 22, 23, 24 and 25 which extend longitudinally of the separator frame. The rolls may be spaced with respect to each other by means of a suitable gauge by which the centers of the rolls may be changed from time to time for the operation of the machine for the selection of granular material of different sizes. Each roll has a drive shaft connected therewith, as represented at 26, 27, 28, 29, 30 and 31, each drive shaft having a bevelled pinion on the extremity thereof, as represented at 32, 33 and 34 which mesh with bevelled gears represented at 35, 36 and 37 which are carried upon a laterally extending shaft 38 journaled within a casing 39, extending laterally of the separator frame the bevel gears 35, 36, 37 etc. are adjustable longitudinally of shaft 38 in proportion to the adjustment in the spacial relationship of the rollers 20, 21, 22, 23, 24 and 25. The casing 39 houses the gearing which drives the sepa-

rator mechanism. A drive pulley 40 may be arranged on the shaft 38 and driven by any suitable prime mover which may be belted at 41 with the drive shaft 40. The 5 separator frame is provided with a hopper 42 by which the material is concentrated upon the system of rolls. Extending laterally across the hopper 42, I provide angle pieces 43 and 44, which may be suitably 10 secured to the side of the hopper by means of adjustable screw devices 44^a and 44^b. The laterally extending angle pieces 43 and 44 contain a plurality of slots which I have represented more clearly in Fig. 6 at 44^c, 15 44^d and 44^e, in which may be laterally and vertically adjusted screw members 49, 50, 51 and 52. As represented more clearly in Figs. 3 and 4 a similar set of screw members 45, 46, 47 and 48 are carried in the laterally 20 extending angle pieces 43 and arranged to be laterally and vertically adjustable therein. The depending screw members are provided with U shaped heads which grip the upper sides of separating plates 53, 54, 55 and 56 25 and permits such plates to be vertically adjusted with respect to the corresponding rolls.

In Fig. 6 I have shown the arrangement by which the guide plates may be raised or 30 lowered with respect to the surface of the rollers to permit granular material of selected size to pass over the rollers. That is to say, the guide plates 53, 54, 55 and 56 may be lowered to establish a very small 35 gap between the lower edges of the plates and the upper surface of rolls 21, 22, 23 and 24 or the gap may be enlarged and this adjustment and spacial relation of the guide plates may be in proportion to the spacial 40 relation and adjustment of the rolls. It will thus be seen that the guide plates form means whereby the granular material which is passed through the separator may be prevented from being carried over against one 45 side of the hopper and compelled to follow a path through the rollers for the selection of desired sizes of material.

While I have described my construction in a certain preferred embodiment, I desire 50 that it be understood that modifications may be made and that no limitations upon the invention are intended other than are imposed by the scope of the appended claims.

What I claim and desire to secure by Letters Patent of the United States is as follows:

1. In a separating or classifying machine, the combination of a hopper, a plurality of downwardly inclined rollers disposed longitudinally of said hopper, a pair of laterally extending members disposed between the sides of said hopper and a plurality of guide plates depending from said laterally extending members and positioned over said rollers, each of said guide plates being ad-

justable toward or away from the rollers aligned therewith in a vertical plane for guiding material to be separated longitudinally along said rollers.

2. In a separating or classifying machine, 70 the combination of a hopper, a plurality of rollers positioned longitudinally of said hopper and spaced one from another for distances equal to the size of material which is to be separated from bulk, a pair of strip 75 members disposed between the sides of said hopper and a plurality of plate members depending from said strip members and extending longitudinally of said rollers and in planes passing through the axis of said 80 rollers for guiding the bulk material against said rollers in the process of separation.

3. In a separating or classifying machine, the combination of a downwardly inclined 85 hopper, a plurality of rollers disposed longitudinally of said hopper, means for rotating said rollers, a pair of strip members laterally positioned across said hopper, a plurality of longitudinally extending plate members parallel with each of said rollers 90 and disposed in planes passing through the axis thereof, said plate members being supported from said strip members relative to said hopper in such manner that material in bulk which is deposited in said hopper 95 is prevented from being carried to one side of the hopper by movement of the rollers.

4. In a separating or classifying machine, the combination of a hopper, a plurality of longitudinally extending rollers disposed in 100 an inclined plane in said hopper, and a plurality of guide plates extending in planes passing through the axis of each of said rollers and arranged to be variably spaced over said rollers in accordance with the size 105 of material to be separated by said machine, said guide plates being supported from said hopper and each guide plate having a thickness less than the gap between said rollers.

5. In a separating or classifying machine, 110 the combination of a hopper, a plurality of longitudinally extending rollers disposed in an inclined plane in said hopper, frame members extending laterally of said hopper, screw members adjustable laterally and vertically within said frame members, said screw members carrying longitudinally extending guide plates which may be positioned in planes passing through the axes of said rollers for guiding the bulk material 120 to be separated over said rollers and preventing the bulk material from being carried to one side of the hopper by movement of the rollers.

6. In a separating or classifying machine, 125 the combination of a hopper, a plurality of longitudinally extending rollers disposed in an inclined plane in said hopper, frame members extending laterally of said hopper, screw members each having a screw threaded 130

shank and a U-shaped head adjustable vertically and laterally within said frame members, longitudinally extending plate members carried in the U-shaped heads of pairs of said screw members in such manner that said plates may be positioned in planes passing through the axis of each of said rollers and adjusted to vary the gap between the

lower extremities thereof and the upper surfaces of said rollers for controlling the size 10 of material separated by said machine and preventing the material from being carried to one side of the hopper by movement of said rollers.

In testimony whereof I affix my signature.
WILLIAM A. RIDDELL.
